[57] CLAIM

The ornamental design for a hibachi stand, substantially as shown.

DESCRIPTION

FIG. 1 is an enlarged isometric view of a hibachi stand showing my new design;

FIG. 2 is a front elevational view thereof;

FIG. 3 is a side elevational view taken from the left of
FIG. 2;

FIG. 4 is a side elevational view taken from the right of
FIG. 2;

FIG. 5 is a top plan view thereof;

FIG. 6 is a rear elevational view thereof;

FIG. 7 is a bottom plan view thereof.

Fig. 1.Fig. 2.Fig. 3.Fig. 5.Fig. 4.Fig. 6.Fig. 7.
